CARPET.

No. 15,975.

Patented Mar. 17, 1885.

UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 15,975, dated March 17, 1885.

Application filed January 14, 1885. Term of patent 3½ years.

To all whom it may concern:

Be it known that I, OTTO HEINIGKE, of New Utrecht, New York, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

The design consists of a connected overlying flower and leaf system and an underlying ground. The overlying system includes various leaf groups (shown black in the photograph) and the black connecting-stems, and scattered star-shaped flowers and larger seven-

pointed circular figures, all carried on the same stems. The ground fills the intervening spaces of the design with small moss-like or lichen-like groups evenly massed over the face of the design.

I claim—

1. The design for a carpet, consisting of the connected system of leaf groups, star-shaped flowers, and large seven-pointed figures, substantially as shown and described.

2. The design for a carpet, consisting of the connected system of leaf groups, star-shaped flowers, and large seven-pointed figures, and the ground, substantially as shown and described.

OTTO HEINIGKE.
